(57) **CLAIM**

The ornamental design for a television receiver, as shown and described.

DESCRIPTION

FIG. 1 is a front perspective view of a television receiver showing our new design;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof;

FIG. 8 is a perspective view of the television receiver in alternate position; and,

FIG. 9 is a perspective view of the television receiver in another alternate position in an environment of use.

The broken lines in the drawings depict portions of the television receiver that form no part of the claimed design.
